UNITED STATES PATENT OFFICE.

WILLIAM CLOW, OF INDEPENDENCE, MISSOURI.

DOWNDRAFT MAGAZINE STOVE AND FURNACE.

1,198,109.

Specification of Letters Patent. Patented Sept. 12, 1916.

Application filed September 20, 1915. Serial No. 51,591.

To all whom it may concern:

Be it known that I, WILLIAM CLOW, a citizen of the United States, residing at Independence, in the county of Jackson and State of Missouri, have invented certain new and useful Improvements in Down-draft Magazine Stoves and Furnaces, of which the following is a specification.

My invention relates to improvements in down-draft magazine stoves, furnaces, etc., and it consists in the peculiar arrangement, construction, and combination of parts, hereinafter described, and more particularly pointed out in the claims.

My object is to provide a stove of simple construction, and so arranged that the greatest efficiency may be obtained with the least consumption of fuel.

In the accompanying drawings, Figure 1 shows a vertical central section of the stove on line I—I of Fig. 2. Fig. 2 is a plan view of the stove with the lid thereof partly broken away. Figs. 3 and 4 are horizontal sections on line III—III and IV—IV, respectively, of Fig. 1. Fig. 5 is a broken vertical section on line V—V of Fig. 2.

In carrying out the invention, I employ an outer shell 1, closed at its ends by a top 2 and a base 3, which latter is supported upon legs 4, so that air currents may pass upwardly through the stove as hereinafter described. The lower portion of the shell 1 has an opening 5 controlled by a damper 6, which may be entirely removed when it is desired to take out ashes from the ash-pit 7 located beneath the grate 8. The top 2 is dome-shaped to form a chamber 9, having an outlet at its rear side communicating with a pipe 10, whereby the products of combustion are carried off.

11 designates an inner shell whereby the interior of the stove is divided into an outer chamber 12 and a hot air chamber 13, which latter is concentrically arranged within the former. The chambers 12 and 13 are divided from the ash-pit 7 and the chamber 9 by a ring 14 and a partition 15, respectively. The outer chamber 12 communicates at its lower end with the ash-pit 7 through an annular opening 16 and at its upper end with the chamber 9 through a plurality of openings 17 in the partition 15. The hot air chamber 13 communicates at its lower end with a plurality of vertical flues 18 supported by the base 3 and they in turn support the ring 14, which has openings 19,

whereby communication is established between the flues and said hot-air chamber 13. The base 3 has a plurality of openings 20, communicating with the lower ends of the flues 18 to admit currents of air thereto. Hot air escapes from the chamber 13 through a plurality of openings 21 and 22 in the top 2 and the partition 15, respectively. Flues 18 are provided near their upper ends with brackets 23, whereby the grate 8 is supported in the upper portion of the ash-pit 7.

24 designates a magazine located within the hot-air chamber 13 and supported upon a fire-pot 25, which in turn is supported above the grate 8 by the ring 14, Fig. 1. Fuel is supplied to the magazine 24 through a hopper 26, depending from the top 2 and resting upon the partition 15. Said hopper 26 is normally closed by a lid 27, having inlets 28 and 29 for the admission of air, inlets 29 being controlled by a damper 30.

Communication is established between the upper end of the magazine 24 and the chamber 9 through a series of openings 31 in the partition 15, and communication through said openings is controlled by an annular valve 32, which also controls communication between chamber 9 and the outer chamber 12, which latter serves as a passage for the products of combustion when the valve 32 is adjusted for down draft. Said valve 32 has peripheral recesses 33 adapted to register with the openings 17, and is provided at its inner edge with recesses 34 adapted to register with the openings 31 in the partition 15, said recesses 33 and 34 being so arranged that when the former registers with the openings 17, the latter will be out of communication with the openings 31, as shown in Figs. 1 and 3. The annular valve 32 has segmental slots 32^a loosely encompassing the surrounding walls of the openings 21.

Valve 32 may be actuated by the lid 27 or by a handle 27^a, through the intermediary of a vertical shaft 35 journaled in the top 2 and the partition 15, a crank 36 fixed to the lower end of said shaft, and a link 37 pivotally-connected to said crank 36 and the valve 32, Fig. 3. The lid 27 is provided with a rearwardly-extending lug 38, having a square hole which loosely encompasses the cylindrical portion of the shaft 35 when said lid is seated in a recess 2^a in the top 2 of the stove, but when the lid is raised

from its recess 2^a, preparatory to being swung to open position, the sides of the square hole in the lug 38 are brought into engagement with the square portion 35^a of 5 the shaft to rotate the same with the lid. The handle 27^a also has a square hole to fit the square upper end 35^a of the shaft 35, so that the same can be rotated to shift the valve 32, without opening the lid 27.

10 39 designates a plurality of scrapers depending from the valve 32 into the chamber 12 to keep the adjacent walls 1 and 11 free from soot.

In starting a fire, an up-draft is created 15 by opening the damper 6 and establishing communication between the magazine 24 and the chamber 9 by turning the valve 32 to uncover the openings 31. After the fire is well under way the draft is reversed and 20 caused to descend through the magazine 24 and the fire-pot 25 by closing the valve 6, opening the damper 30 and adjusting the valve 32 to close the openings 31 and uncover the openings 17. As the air in the 25 chamber 13 becomes heated it ascends and escapes through the openings 21 and 22, and draws cold air from beneath the stove upward through the flues 18.

The currents of air passing upwardly 30 through the chambers 12 and 13 prevent the shells 1 and 11 from burning out and add largely to the heating capacity of the stove. When the lid 27 is opened to replenish the fuel the openings 31 are 35 uncovered to allow the smoke to pass upwardly therethrough instead of escaping through the hopper 26 into the room containing the stove.

While I have shown the invention applied 40 to a stove, it is obvious that it can be readily embodied in a furnace without departing from the spirit and scope of the invention.

Having thus described my invention, what 45 I claim and desire to secure by Letters Patent, is:

1. In a stove, an upper chamber having an outlet, an outer annular chamber communicating with said upper chamber, a magazine also communicating with said upper chamber, an intermediate chamber be-

tween said outer chamber and the magazine, a fire-pot communicating with said magazine and having communication at its lower end with the outer chamber, a grate beneath said fire-pot, and a valve for alternately closing communication between the magazine and the upper chamber and between the outer chamber and said upper chamber. 55

2. In a stove, an upper chamber having an outlet, an outer chamber communicating 60 with said upper chamber, a magazine also communicating with said upper chamber, a fire-pot communicating with said magazine and the outer chamber, a grate beneath said fire-pot, a hopper extending through the 65 upper chamber and communicating with the magazine, a lid upon said hopper provided with inlets for the admission of air, a damper to control said inlets, a valve for alternately closing communication between 70 the magazine and the upper chamber and between the outer chamber and said upper chamber, and means connecting said valve to the lid whereby the latter actuates the former. 75

3. In a stove, an ash-pit in the lower portion thereof and outlets in its upper portion, a ring at the top of the ash-pit, a fire-pot supported by said ring, a magazine supported by said fire-pot, a shell supported by 80 the ring and surrounding the fire-pot and the magazine to form a hot-air chamber communicating with the outlets in the upper portion of the stove, and inlet flues supporting the ring and communicating at 85 their upper ends with the hot-air chamber.

4. In a stove of the character described, two concentric chambers, an upper chamber communicating with one of said concentric chambers, a valve for controlling such communication, and scrapers depending from 90 said valve to keep the adjacent walls of the concentric chambers clean.

In testimony whereof I affix my signature, in the presence of two witnesses.

WILLIAM CLOW.
